(57) **CLAIM**

The ornamental design for a lid for drinking bottle, as shown and described.

DESCRIPTION

FIG. 1 is a right side view of the lid for drinking bottle, the left side being a mirror image thereof.

FIG. 2 is a front view of the lid for drinking bottle.

FIG. 3 is a rear view of the lid for drinking bottle.

FIG. 4 is a top view of the lid for drinking bottle.

FIG. 5 is a bottom view of the lid for drinking bottle.

FIG. 6 is a front, top, right side perspective of the lid for drinking bottle in the closed position.

FIG. 7 is a rear, top, right side perspective of the lid for drinking bottle in the closed position.

FIG. 8 is a front, top, right side perspective of the lid for drinking bottle in the open position; and,

FIG. 9 is a rear, top, right side perspective of the lid for drinking bottle in the open position.

In the drawings, the broken lines illustrate portions of the article which form no part of the claimed design.
